HAIR CLIPPERS OR SIMILAR ARTICLE

Rudolph J. Enstrom and Oscar R. Sandstrom,
Crystal Falls, Mich.

Application December 10, 1949, Serial No. 6,552

Term of patent 7 years

(Cl. D22—5)

To all whom it may concern:

Be it known that we, Rudolph J. Enstrom and Oscar R. Sandstrom, both citizens of the United States, and residents of the city of Crystal Falls, in the county of Iron and State of Michigan, have jointly invented a new, original, and ornamental Design for Hair Clippers or Similar Article, of which the following is a specification, reference being had to the accompanying drawing, forming a part thereof.

On the drawing:

Figure 1 is a top plan view of the hair clippers or similar article, showing our new design;

Figure 2 is a side elevational view thereof; and

Figure 3 is a front elevational view thereof with the clipper mechanism removed for convenience of illustration.

The essential features of our design reside in those portions shown in full lines.

We claim:

The ornamental design for hair clippers or similar article, as shown and described.

RUDOLPH J. ENSTROM.
OSCAR R. SANDSTROM.
